UNITED STATES PATENT OFFICE.

MORRIS C. HOLE, OF MCKITTRICK, CALIFORNIA, ASSIGNOR OF ONE-HALF TO DEE B. WILLCUTS, OF MCKITTRICK, CALIFORNIA.

PUMPING JACK.

Application filed August 3, 1922. Serial No. 579,530.

To all whom it may concern:

Be it known that I, MORRIS C. HOLE, a citizen of the United States, residing at McKittrick, in the county of Kern and State 5 of California, have invented a new and useful Pumping Jack, of which the following is a specification.

This invention relates to pumping-jacks for well pumps and is particularly directed 10 to a type of pumping-jack especially adapted for use in connection with oil wells.

One of the best known types of pumping-jack which is universally referred to as the "Oklahoma jack," comprises a substantially 15 horizontally positioned top beam which is pivoted at its rear end to a supporting structure with its free or forward end connected to the polish or pump rod, a pivoted triangular rock-frame having a vertical arm to 20 which the power cable is attached to rock said frame and a forwardly extending arm, and a push rod between the forwardly extending arm of said frame and the free end of the top beam, whereby the horizontal 25 pull of the power cable is converted to an arcuate movement of the free end of the top beam in a more or less general vertical direction.

This arcuate movement, while of large 30 radius, causes a very undesirable side thrust on the polish-rod at every stroke with the result that the stuffing-box through which the rod reciprocates becomes so worn as to render it exceedingly difficult to maintain 35 said stuffing box packed sufficiently to prevent a loss of oil. Further such side thrust absorbs an appreciable amount of the applied pumping power.

It is an object of the present invention to 40 provide a pumping-jack by which the horizontal pull or reciprocation of the power cable is converted into a true vertical movement and applied to the pump rod, whereby side thrust of the pump rod is eliminated.

Another object is to provide a pumping-jack structure which is exceedingly simple, durable and efficient, and which can be easily and quickly applied to the pump mechanism, or removed therefrom to afford easy 50 access to said mechanism.

A further object is to provide a pumping-jack in which it is possible to incorporate certain standard parts of the well known "Oklahoma jack."

Another object is to provide a pumping-

jack having an overhanging or eccentric connection with the pump rod and apply the actuating force in a direction which will operate to neutralize or counteract any side thrust occasioned at the guide bearings by 60 the weight of the pump rod and column of oil within the pump.

Various other objects and advantages will be more fully apparent from the following description of the accompanying drawings, 65 which form a part of this disclosure, and which illustrate a preferred form of embodiment of the invention.

Of the drawings:

Fig. 1 is a side elevation of my improved 70 pumping-jack applied to the ordinary type of oil well pumping mechanism.

Fig. 2 is a front elevation, and

Fig. 3 is a rear elevation.

In the drawings, 1 designates the usual 75 casing head, 2 the pump tubing, and 3 the polish or pump rod which reciprocates through the stuffing-box 4.

Rearwardly of the casing-head 2 are spaced sill blocks 5 to which are secured stationary pivot connections or bearing plates 6 to receive the trunnions 7 of a triangular rock-frame 8. The rock-frame 8 has a vertical arm connecting with the terminal fitting 9 of a power cable, and a forwardly extending horizontal rocking arm 10 which is provided with a pivot block 11. This frame as illustrated, is of the standard Oklahoma type, but in so far as the broad aspect of the invention is concerned, it may be of other 90 specific construction suitable for the purpose.

I provide a substantially vertically guided slide for imparting movement from the rocking frame to the pump rod. For this 95 purpose pivotally connected at 12 to the sills 11, is a guide frame having lateral side rails 13 extending forwardly on opposite sides of the rock-frame 8 and joined respectively to relatively spaced uprights 14. Said uprights are joined together by vertically spaced bearing members 15 and to each upright is connected a diagonal brace 16 extending rearwardly and downwardly and joined to the respective side rail, thus forming 100 a rigid frame structure.

The bearing members 15 of the guide frame have vertically aligned bores to receive a vertical guide rod 17 and said guide rod has at its lower end a pivot member 18 110

engaging into a pivot seat 19 carried by the upper end of a connecting-rod 20, the lower end of said connecting-rod being provided with a pivot member engaging the pivot block 11 of the rock-frame 8.

Clamped upon the guide-rod 17 between the bearings 15 is a saddle member 21 having a bifurcated outer end with the forks engaging beneath opposite trunnions of an adjuster 22 secured upon the polish or pump rod 3.

This provides an overhanging connection between the guide rod 17 and pump rod 3, and to overcome any tendency of the guide rod 17 exerting any appreciable side thrust on the upper bearing 15, on account of the eccentric point of application of the weight of the pump rod and oil column, I position the toe of the rock-frame 8 slightly rearwardly of the vertical axial plane of the guide rod 17.

Hence the actuating force from the rock-ing frame is imparted in an inclined upward direction, and this direction for this force operates to develop re-action forces in the guide blocks or bearings 15 which oppose the re-action forces that would naturally be developed by the downward pull on the pump-rod.

By the above described structure, the horizontal pull in of the power cable is converted into a true vertical movement in a plane parallel to the polish or pump rod, whereby all side thrust on the pump rod is eliminated.

In disconnecting the pumping-jack, the pump-rod is elevated to disengage the adjuster 22 from the saddle member 21, the pivotal member 18 being disengaged from the pivot seat 19, and the guide frame swung backward independently of the rock-frame, which may also be subsequently swung backward if desired.

With such an organization of parts the jack may be easily and quickly disconnected without the necessity of disturbing any element thereof, such as bolts, screws, or clamps, and may in the same manner be reconnected when desired.

It is advisable, in order to counteract the pull in the pump head, that the point of application of the thrust in the connecting rod should be at a point outside of the space between the guide blocks. It is more convenient to have this point of application at the lower end of the slide; that is to say, below the lower guide block.

A jack of this character eliminates all of the objectional features of the "Oklahoma jack" and does away with the cumbersome and expensive top beam and heavy supporting structure thereof, and further it provides a pumping-jack which embodies great strength, freedom of vibration, simplicity of construction, and ease of manipulation.

While the specific construction herein illustrated and described is well adapted for the purposes primarily stated, it is to be understood that I do not wish to limit the invention to the one form disclosed, for it is susceptible of embodiment in various forms, all coming within the scope of the following claims.

I claim:

1. In a pumping-jack, a pump operating rock-frame, an independent guide structure, a guide rod disposed with its longitudinal axis substantially vertical and mounted to slide substantially vertically in said structure, a connecting rod having a pivotal connection with said rock frame and with the lower end of the guide rod, and means carried by said guide rod and adapted to engage a pump rod.

2. In a pumping-jack, a pump operating rock-frame, an independent guide structure pivoted to swing from position of use independently of the rock-frame, a guide rod mounted to slide substantially vertically in said structure, a connecting rod having a pivotal connection with said rock frame and with the guide rod, and means clamped on said rod and adapted to engage a pump rod.

3. In a pumping-jack for operating a well pump, a pump operating rock-frame pivoted at its rear end with its forward end terminating at a point located rearwardly of the pump rod, an independent guide structure, a guide rod mounted to slide in said structure in a substantially vertical plane between the pump rod and the forward end of the rock-frame, a connecting rod pivotally engaging the forward end of the rock-frame and the lower end of the guide rod, and means connecting the guide rod and pump rod.

4. In a pumping-jack for operating a well pump, a stationary pivot connection, a pump operating rock-frame pivotally engaging said connection, a guide frame hinged to swing from its position of use, a guide rod mounted to slide substantially vertically in said guide frame, a connecting rod pivotally connecting the rock-frame and the guide rod, and means connecting the guide rod and pump rod for actuating the latter.

5. In a pumping-jack for operating a well pump, a stationary pivot connection, a pump operating rock-frame pivotally engaging said connection, a guide frame hinged to swing from its position of use and having vertically spaced bearings, a guide rod mounted to slide substantially vertically in said bearings, a connecting rod pivotally engaging the rock-frame and the lower end of the guide rod, and means clamped to the guide rod between said bearings and adapted to engage the pump rod.

6. In a pumping jack, a guide frame having guide blocks, a slide guided to slide sub-

stantially vertically through said guide blocks, said slide having means on one side for engaging the pump rod, whereby reaction forces are developed at said blocks acting upon the slide, a rocking frame, and a member between the rocking frame and slide and imparting the actuating force to the slide at a point outside of the space between the guide blocks in an upward and inclined direction and operating to develop reactive forces in the guide blocks opposed to the first named reactive forces.

7. In a pumping-jack for operating a well pump, the combination of a guide frame having guide blocks, a slide guided to slide substantially vertically through said guide blocks, said slide having means on one side for engaging the pump rod whereby reaction forces are developed by the pull of the pump rod at said blocks acting upon the slide, a connecting rod engaging the slide on the opposite side from the pump rod, a rocking-frame having a rocker arm with its rocking end disposed near the slide having a connection with the lower end of the connecting rod and operating to move the lower

end of the connecting rod up and down in an arc about in alignment with the line of movement of the slide whereby the upward thrust of the rod exerted upon the slide 30 counteracts the reaction forces developed in the same by the force exerted by the pump rod.

8. In a pumping-jack, the combination of a guide frame, a slide guided to slide substantially vertically in the guide frame, said slide having means on one side for engaging the pump rod, a rocking arm mounted with its rocking end disposed about in alignment with the line of movement of the slide, a 40 connecting rod between the rocking end of the rocker arm and the lower end of the slide and having a pivot-and-seat connection respectively with the slide and with the rocker arm, the end of said rocker arm operating to move up and down in an arc and exerting an upward thrust in the connecting rod in each upward movement of the arm.

Signed at McKittrick, California, this 19th day of July, 1922.

MORRIS C. HOLE.
